UNITED STATES PATENT OFFICE.

CASSELL D. HIBBS, OF FORT WORTH, TEXAS.

MACHINE FOR BUFFING INNER TUBES AND THE LIKE.

1,319,338.

Specification of Letters Patent. Patented Oct. 21, 1919.

Application filed June 2, 1919. Serial No. 301,152.

To all whom it may concern:

Be it known that I, CASSELL D. HIBBS, a citizen of the United States of America, residing at Fort Worth, in the county of Tarrant and State of Texas, have invented certain new and useful Improvements in Machines for Buffing Inner Tubes and the like, of which the following is a specification.

10 My invention relates to improvements in buffing machines and more particularly to machines for buffing inner tubes and various articles; and the object is to provide machines which will be highly efficient in buffing inner tubes and fabrics of various composition, and to provide machines which are readily adjustable to various widths and thicknesses of material and which will aid in feeding material forward to be buffed. 15 Other objects and advantages will be fully explained in the following description and the invention will be more particularly pointed out in the claims.

Reference is had to the accompanying drawings which form a part of this application.

Figure 1 is a front elevation of the machine. Fig. 2 is a side elevation of the same. Fig. 3 is a side elevation, being the opposite side of the machine as shown in Fig. 2. Fig. 4 is a horizontal section, taken on the line 4-4 of Fig. 1. Fig. 5 is a detail view, illustrating the eccentric bearings of the feed rollers, being shown on an enlarged scale.

Similar characters of reference are used to indicate the same parts throughout the several views.

The machine is provided with an upright frame consisting of members 1 and 2 which are braced by the cross brace 3 and also by the hood 4. The revolving buffer 5 is provided with a shaft 6 which is journaled in the frame members 1 and 2. A power pulley 7 is rigid with the shaft 6 for driving the machine. Any suitable power may be used to drive the pulley 7. This pulley drives the buffer 5 and the pulley 8. The pulley 8 drives a cross belt 9 which drives the wheel 10 which drives shaft 11. The shaft 11 drives a pulley 12. The pulley 12 drives the belt 13 which drives the wheel 14 which drives the shaft 15. A sprocket wheel 16 is rigid with shaft 15 and drives

the sprocket chain 17. The sprocket chain 17 drives the sprocket wheel 18. The wheel 18 is rigid with the shaft 19 for driving this shaft and the roller 20 which is the feed roller or bearing roller over which the material is passed to be operated upon by the buffer 5. The roller 20 might be driven too fast, that is, the action of the buffer 5 might draw the material over the roller 20 too fast, causing the material to pass before sufficiently reduced by the buffer 5. This can be regulated to some extent by the roller 21 which is journaled in the upper end of a foot lever 22 which is fulcrumed on the frame member 2. A spring 23 is attached to the frame 2 and to the upper end of the lever 22 and this spring will normally hold the roller 21 against the belt 13 to cause this belt to drive the wheel 14. A pressure of the foot on the lever 22 will release the pressure of the roller 21 on the belt 13 and thus stop the wheel 14 from turning. This makes the operation or turning of the roller 20 under the control of the foot of the operator. The feeding of the rubber tube or other material to the roller 20 is regulated by a roller 24 which is journaled eccentrically in bearings 25 which are journaled in the swinging frame 26. A shaft 27 on which the roller 24 is mounted is eccentrically mounted in the roller bearings 25. A crank handle 28 is rigid with the shaft 27 and by means of this handle 28 the roller 24 may be made to bear with more or less pressure against the material which is passing over the roller 20. The swinging frame 26 is loosely mounted on the shaft 15. A pulley wheel 29 is rigid with the shaft 34 and a cord or belt 30 is attached to the wheel 29 and extended over a pulley 31 which is mounted on shaft 15 and a weight 32 is attached to the end of the cord 30. By means of this construction and disposition of elements, the swinging frame 26 may be held in different positions. The frame 26 is provided with a handle 33 for convenience in moving this frame. The frame 26 is adjusted to different positions by means of cams 35 which are rigid with the shaft 34. A handle 36 is rigid with shaft 34 for convenience in lifting the frame 26 to different positions. When the handle or crank 36 is moved the shaft 34 changes the position of the cams 35 if the handle is raised and if the

handle is lowered, the cams will be lowered and the frame will follow the cams downwardly. The weight 31 and the cams 35 hold the frame 26 in whatever position to 5 which the frame is adjusted.

What I claim, is,—

1. A buffing machine comprising a rigid frame, a revolving buffer provided with a shaft journaled in said frame, a feeding 10 mechanism consisting of a bearing roller, means for adjusting said roller relative to said buffer, means for holding said roller in different positions, a cam-adjustable roller coöperating with said bearing roller, and 15 means for driving said rollers from said shaft.

2. A buffing machine comprising a rigid frame, a revolving buffer provided with a shaft journaled in said frame, a feeding 20 mechanism consisting of a bearing roller, a swinging frame carrying said roller, cams and a shaft therefor for adjusting said swinging frame, means for holding said swinging frame in different adjustments, a 25 feed roller coöperating with said bearing roller, cam-actuated means for adjusting said feed roller relative to said bearing roller, and means for driving said rollers from said buffer shaft.

3. A buffing machine comprising a rigid frame, a revolving buffer provided with a shaft journaled in said frame, a feeding mechanism consisting of a bearing roller, a swinging frame carrying said roller, cam- 35 actuated means for adjusting said frame to different positions, a weight controlled means for holding said frame in different

positions, and means for driving said roller from said buffer shaft.

4. A buffing machine comprising a rigid 40 frame, a revolving buffer provided with a shaft journaled in said frame, a feeding mechanism consisting of a bearing roller, a swinging frame carrying said roller, cam-actuated means for adjusting said frame to 45 different positions, a weight controlled means for holding said frame in different positions, driving mechanism operatively connected with said buffer shaft and with said roller for driving the roller, and a foot 50 lever fulcrumed on said frame and operatively connected with said roller driving mechanism for stopping and starting the roller driving mechanism.

5. A buffing machine comprising a rigid 55 frame, a revolving buffer provided with a shaft journaled in said frame, a feeding mechanism consisting of a bearing roller, a swinging frame carrying said roller, cam-actuated means for adjusting said roller to 60 different positions, a weight controlled means for holding said frame in different positions, a feed roller, roller bearings mounted in said swinging frame, a shaft carrying said feed roller and eccentrically 65 mounted in said roller bearings, means for actuating said bearings to adjust said feed roller relative to said bearing roller, and means for driving said rollers from the 70 shaft from said buffer shaft.

In testimony whereof I set my hand, this 28th day of May, A. D., 1919.

CASSELL D. HIBBS.
